UNITED STATES PATENT OFFICE.

DEAN N. SWIFT, OF RIDGWAY, PENNSYLVANIA.

WINDOW-VENTILATOR.

No. 833,260.

Specification of Letters Patent.

Patented Oct. 16, 1906.

Application filed May 14, 1906. Serial No. 316,847.

To all whom it may concern:

Be it known that I, DEAN N. SWIFT, a citizen of the United States, residing at Ridgway, in the county of Elk, State of Pennsylvania, have invented certain new and useful Improvements in Window-Ventilators, of which the following is a specification, reference being had therein to the accompanying drawings.

This invention relates to a window-ventilator, and particularly to a casing adapted to be interposed between the rail of the sash and the top or bottom of the window-frame. The invention has for an object to provide a telescoping casing adapted for application to a window-frame and provided with an interior partition curved for a portion of its length concentric with the wall of the casing and its upper end diverging from said wall, so as to provide an enlarged discharge-opening and prevent a direct upward flow of the draft, which would disturb a shade or curtain, and to diffuse the air entering therethrough.

A further object of the invention is to provide means for supporting the ventilator-casing in position either upon the window-frame or upon the sash therein.

Other and further objects and advantages of the invention will be hereinafter set forth and the novel features thereof defined by the appended claims.

In the drawings, Figure 1 is an elevation of a window with the ventilator applied at the top and bottom thereof. Fig. 2 is a vertical section on the line 2 2, Fig. 1. Fig. 3 is a detail perspective of the ventilator removed from the window. Fig. 4 is a vertical section on the line 4 4, Fig. 3, and Fig. 5 is an enlarged vertical section through the ventilator for the upper sash.

Like numerals of reference indicate like parts in the several views of the drawings.

The numeral 1 designates a window-frame, which may be provided with a lower sash 2 and an upper sash 3, the same being of any desired construction or configuration. The ventilator 4 is formed in two sections telescoping and slidingly mounted upon each other, so as to be adjustable for windows of different widths, and each of these sections is provided with an end wall 5, while the inner face of the ventilator is curved, as shown at 6, and provided with a flat seat 7 at its base. Within the casing a curved partition 8 is secured and for a portion of its length extends

concentric with the outer wall 6, thus forming a curved passage 9, through which the air passes in entering the room and which prevents any direct inward or upward draft. 60 The upper portion of this partition is deflected from the wall 6, as shown at 10, thus providing an enlarged discharge portion to permit the diffusion of the air and its delivery into the room at a point removed from the 65 sash, so that the curtain or shade will not be disturbed by the entering air. The casing is open at its outer face and is provided with the depending lug 11, adapted to seat either upon the outer face of the sill 12 at the lower 70 portion of the sash or the outer face of the top rail 13 of the upper sash.

In its main features the construction of the ventilator used for the top and bottom of the window are similar, excepting so far as 75 the means for supporting them in position, and for this purpose the lower ventilator is provided with a slot 14 in each of its end walls, terminating in an enlarged opening 15, through which the head of the screw 16 may 80 be passed and the ventilator slid downward until the shank of the screw enters the slot 14. This method of attachment retains the sections of the telescoping casing against movement upon each other and also against 85 movement laterally on the sash, while the lower portion of the casing is held by the lug 11 against such movement. The opening through which the air may enter the casing is adapted to be varied by an adjustment of 90 the elevation of the lower rail 17 of the lower sash, as will be seen in Fig. 1.

The upper ventilator is adapted to be mounted upon the rail 13 of the upper sash by means of the plate 18, which, in connection with the lug 11, embraces this rail. It will be obvious that this plate can be omitted and the casing retained by the lug 11 and the contact of the top of the casing with the surface of the window-frame.

The operation of the invention will be understood from the foregoing description, and it is adapted to be applied to either the top or bottom of the window or in both positions, while the bottom ventilator herein shown 105 can be used in either position, as found desirable. The construction of the casing with the curved partition to direct the entering current of air is adapted to secure the most efficient results, while avoiding drafts in the 110 room adjacent to the window, and embodies the same in a simple and economical con-

struction. The means for attaching the casing is adapted to hold the same against any movement relative to the sash or accidental displacement when in use, while either of the ventilators can be quickly and conveniently removed when found desirable.

Having now described my invention and set forth its merits, what I claim, and desire to secure by Letters Patent, is—

1. A window-ventilator comprising a casing provided with end walls and curved face, and a partition extending for a portion of its length concentric with said face and diverging therefrom at its upper portion to provide an enlarged discharge-opening.

2. A window-ventilator comprising a casing provided with end walls and curved face, a partition extending for a portion of its length concentric with said face and diverging therefrom at its upper portion to provide an enlarged discharge-opening, a supporting-base for said casing, and a depending lug at one side of said base.

3. A window-ventilator comprising a casing provided with end walls and curved face, a partition extending for a portion of its length concentric with said face and diverging therefrom at its upper portion to provide an enlarged discharge-opening, and headed securing devices carried by the frame of the window at each end of said casing and adapted to enter a slot therein.

4. A window-ventilator comprising a casing formed of telescoping sections each provided with one end wall and with a curved inner face extending downward to the supporting-base, and a telescoping partition secured to the end wall of each section and extending at its lower portion concentric with the curved wall of the casing and diverging therefrom at its upper portion.

In testimony whereof I affix my signature in presence of two witnesses.

DEAN N. SWIFT.
